CLAIM

The ornamental design for a connector for LED flexible light bar, as shown and described.

DESCRIPTION

FIG. 1 is a front elevation view of a connector for LED flexible light bar showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a top perspective view thereof;

FIG. 8 is a bottom perspective view thereof;

FIG. 9 is a top perspective view shown in a state of use thereof; and,

FIG. 10 is a bottom perspective view shown in a state of use thereof.

The broken lines in the drawings depict portions of the connector for LED flexible light bar that form no part of the claimed design.

1 Claim, 10 Drawing Sheets
